CLAIM

The ornamental design for an inflatable float, as shown and described.

DESCRIPTION

FIG. 1 is a front, left, bottom perspective view of an inflatable float, showing the new design;

FIG. 2 is a rear, right, top perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the inflatable float, that form no part of the claimed design. The appearance of any portion of the inflatable float shown between the break lines forms no part of the claimed design.

1 Claim, 8 Drawing Sheets
